Primary Examiner — Kevin K Rudzinski*(74) Attorney, Agent, or Firm* — Lambert Shortell & Connaughton; David J. Connaughton, Jr.(57) **CLAIM**

The ornamental design for a shawl with hook and loop closure, as shown and described.

DESCRIPTION

FIG. 1 is bottom perspective view of the shawl with hook and loop closure showing my new design;

FIG. 2 is a bottom view of the back of the shawl with hook and loop closure;

FIG. 3 is a top view of the shawl with hook and loop closure;

FIG. 4 is a side view of the shawl with hook and loop closure;

FIG. 5 is a side view of the shawl with hook and loop closure;

FIG. 6 is a side view of the shawl with hook and loop closure;

FIG. 7 is a side view of the shawl with hook and loop closure; and,

FIG. 8 is an isometric view of the front of the shawl with hook and loop closure.

The dotted line depiction of the human is shown to demonstrate the design in a position of use and is not part of the claimed design.

1 Claim, 5 Drawing Sheets(56)
